ATTORNEY.

of the web adjacent to it, this portion being designated by the reference numeral 25. The peripheral edges of the cored portions may advantageously be formed with rigidifying or strengthening flanges or beads 14 whereby all of the various members of the cross bearer are of rail shape.

At its ends the cross bearer is formed with substantially vertical flanges 28 affording convenient means to which the side sheets 4 of the car may be rigidly secured. Overlapping the inner faces of the side sheets are side stakes 5, each of which is formed by two angle members arranged so that one flange of each may be rigidly connected while the other flange of each may be secured to the adjacent side sheet. The upper portions of the side stakes incline upwardly as at 6 and terminate slightly below the side top rails 8 which may be reinforced by brackets 7 overlapping the outer faces of the side sheets and rigidly secured to the inclined portions of the side stakes.

Adjacent its ends the bearer is formed, preferably integrally, with upstanding lugs 26 having a substantially vertical portion to the opposite sides of which the angle members of adjacent side stakes 5 may be secured. Inwardly of the lugs 26 the cross bearer is also formed with upstanding brackets 20 and 21, respectively, to which struts or members 22 may be rigidly connected to brace the side stakes and consequently the side walls of the car. These braces are preferably of rail shape having a flange 44, a web portion 45 and a rigidifying bead or flange 46. Each of the brackets 20 and 21 is formed with an upwardly and outwardly extending plate portion 47 which may be rigidified by a triangularly-shaped portion 48 disposed in the plane of the web of the cross bearer and thereby constituting a continuation thereof. The plate portions 47 of the brackets afford convenient means to which the flanges 44 of the struts may be secured and in order to more firmly secure the struts to the cross bearer the lower ends of their flanges 44 are bent or angled inwardly as at 34 so that they may be riveted directly to the top flange 15 of the cross bearer. The upper ends of each of the struts is preferably flattened as at 23 so that they may be conveniently secured to adjacent side stakes. As a convenient means for connecting the struts and side stakes the flanges of the latter which are secured together are preferably spread apart to form pockets 9 into which the flattened ends 23 of the struts may be inserted. From this manner of connecting the struts to the side stakes and cross bearer it will be perceived that the side walls are effectively braced.

To rigidify the cross bearer adjacent the brackets 20 and 21 it is preferably formed

with oppositely disposed laterally projecting web portions or flanges 39 and 40 respectively. These flanges, as may be seen from the drawings, are of substantially triangular-shape, merging at their lower ends with the web portion 24 of the upper member of the cross bearer and are preferably disposed in substantially the same planes as the plate portions 47 of the brackets to thereby constitute continuations thereof. In this manner any torsional movements set up in the top flange 15 of the cross bearer due to the connection between the latter and the struts 22 are effectively resisted.

Adjacent its lower central portion the cross bearer may be advantageously integrally formed with depending brackets 29 for attachment to the center sill. Each of these brackets is formed with a plate portion 30 of substantially triangular-shape rigidly secured by rivets 33 in overlapping relation to the outer faces of the center sill beams. The plate portions 30 extend on opposite sides of the bottom flange 16 of the cross bearer and merge with the web portion of the latter, as at 32, a considerable distance above the lower edge of the bearer. If desired, each of the brackets may be formed with a triangularly-shaped rigidifying flange 31 disposed in substantially the same plane as the main web portion of the cross bearer. At its ends, the cross bearer is integrally formed with depending brackets 27 for attachment to the upstanding legs of the adjacent side sills 3. The outer faces of the brackets 27 are preferably offset slightly inwardly so that portions of the side sills may be interposed between the cross bearer and the side sheets 4 of the car without offsetting the latter.

Diverging downwardly on opposite sides of the cross bearer are hopper sheets A which preferably extend continuously from one side of the car to the other and are formed with upstanding marginal flanges for attachment to the adjacent side sheets 4. The upper portions of the hopper sheets are formed with substantially vertical flanges 49 for attachment to the web portion 24 of the upper member 11 of the cross bearer by rivets 43. Adjacent the reinforcing flanges or webs 39 and 40 the hopper sheet is cut away so that these flanges will not interfere with the attachment of the latter to the cross bearer.

Projecting from opposite sides of the cross bearer adjacent the reinforcing flanges 39 and 40 are laterally extending portions 42, the upper surfaces of which are disposed in planes substantially parallel with the inclined planes in which adjacent portions of the hopper sheets are disposed for supportingly cooperating with the latter. These projections 42 not only serve to prevent the escape of fine lading through the cut out 130

portions 37 and 38 of the hopper sheets but they also effectively serve as means for supporting the inclined portions of the sheets intermediate their ends.

- 5 Inasmuch as the hopper sheets inclose all of the cross bearer with the exception of its top flange 15 the bearer will not be subjected to the detrimental and injurious effects of acids contained in lading shipped 70
 10 in the car as well as moisture which may be contained in the lading. Furthermore, inasmuch as the upper edges of the flanged portions of the hopper sheets terminate adjacent the top flange 15 of the cross bearer, 75
 15 moisture is more or less prevented from seeping between the hopper sheets and adjacent portions of the bearer thereby preventing rapid corrosion of these contacting parts.
 20 From the foregoing it will be perceived that I have provided a cross bearer of extremely rigid construction and one that may be easily and conveniently secured to adjacent parts of the car structure. Also sim- 80
 25 ple and rugged means is provided whereby struts for bracing the side walls may be rigidly secured to the cross bearer and the manner of connecting the hopper sheets to the cross bearer insures a more lasting and 85
 30 durable construction.

I claim:—

1. A cross bearer for railway hopper cars of integral formation and provided with arms adapted to be locked to side stakes of 90
 35 the car, the upper member of the cross bearer adapted to receive the upper edges of hopper sheets for supporting the latter.
2. A cross bearer for railway hopper cars comprising an upper and a lower member 100
 40 and integral diagonals connecting said members, the upper member being adapted to receive the upper edge of hopper sheets to thereby support the same.
3. A cross bearer for railway hopper cars 105
 45 comprising an upper and a lower member and integral diagonals connecting said members, the cross bearer being adapted to be disposed between downwardly diverging hopper sheets which are secured to the said
 50 upper member whereby just the upper edge of the cross bearer will extend above the hopper sheets.
4. In a railway hopper car, the combination with a center sill, of a one-piece cross 110
 55 bearer having arms extending diagonally upward from adjacent the sides of the sill to the top of the cross bearer, and downwardly diverging hopper sheets secured to the upper edge of the cross bearer.
5. In a railway hopper car, the combination with center sill, of a one-piece cross 115
 60 bearer having upper and lower members and integral diagonals connecting the latter, arms extending upwardly from the upper
 65 member and adapted to be tied to side stakes

of the car, hopper sheets, and means for rigidly securing the hopper sheets to the opposite faces of the upper member of the cross bearer.

6. In a railway hopper car, the combination with a one-piece cross bearer having separable arms extending diagonally upward from the said cross bearer and adapted to be tied to side stakes of the car, said cross bearer comprising an upper and a lower member, diagonals joining said members, lugs rigid with said top member, and hopper sheets resting on said lugs and riveted of said top member. 70
 75

7. A cross bearer substantially in the form of an I-beam, the web of the beam being cored to form diagonals between the upper and lower members of the beam, brackets rigid with the upper member of the cross bearer, diagonal arms adapted to be secured to said brackets and to side stakes of the car, and means along the upper member of the cross bearer to receive and support hopper sheets. 80
 85

8. A cross bearer comprising a top flange, a web and a bottom flange, the web being cored to form in substance a top member, diagonals and a bottom member, the said cored portions each having a peripheral flange about its edge, thereby making the 90
 95 diagonals rail-shape in cross section and also making the upper and lower members rail-shape in cross section.

9. A cross bearer comprising a top flange, a web and a bottom flange, the web being 100
 105 cored to form in substance a top member, diagonals and a bottom member, the said cored portions each having a peripheral flange about its edge, thereby making the diagonals rail-shape in cross section and also making the upper and lower members rail-shape in cross section, and means on the upper member adapted to support and hold the upper edge of a hopper sheet. 110

10. A cross bearer comprising a top flange, a web and a bottom flange, the web being 115
 120 cored to form in substance a top member, diagonals and a bottom member, the said cored portions each having a peripheral flange about its edge, thereby making the diagonals and the upper and lower members of rail-shape in cross section, the upper member provided with rivet holes for receiving means for attaching hopper sheets to the cross bearer, and means projecting from opposite sides of the cross bearer for supportingly cooperating with the hopper sheets. 125

11. A cross bearer comprising a top flange, a web and a bottom flange, the web being 125
 130 cored to form in substance a top member, diagonals and a bottom member, the said cored portions each having a peripheral flange about its edge, thereby making the diagonals and the upper and lower members 130

- of rail-shape in cross section, and projections on the opposite faces of the upper member for supporting adjacent hopper sheets of the car.
- 5 12. A cross bearer comprising a steel casting having an upper member, a lower member, metal connecting said members, relatively short seats formed on the opposite faces of the upper member for supporting 10 hopper sheets of the car and said upper member being provided with a series of holes for receiving rivets to tie the hopper sheets to said cross bearer.
13. A cross bearer, the body of which is 15 a unitary casting, brackets formed on the upper member, arms adapted to be secured to said brackets and to the side stakes of a car, projections on the upper member below said brackets for supporting hopper sheets 20 of the car and the upper member being provided with holes for receiving rivets to secure the hopper sheets thereto.
14. A cross bearer, the body of the same being a unitary casting, said cross bearer 25 having a marginal flange extending completely about the same, the body of the bearer being cored to form diagonals and the peripheries of the cored portions being provided with flanges, brackets on the bottom 30 of the bearer adapted to be secured to the center sill and side sills of the car, and brackets on the upper member adapted to be secured to upwardly extending arms for bracing the sides of the car.
- 35 15. A cast steel cross bearer, the body of which is cored to provide diagonals between the upper and lower portions thereof, inclined brackets formed on the upper member, arms secured to said brackets, lugs adjacent the opposite ends of the upper portion of the bearer adapted to be secured to side stakes of the car, and brackets on the bottom portion of the bearer adapted to be secured to the center sill and side sills of the 40 car.
- 45 16. A cross bearer adapted to fit down between the adjacent hopper sheets of a freight car, said cross bearer comprising an integral body and upstanding separable arms for attachment to side stakes of the car, means along the lower edge of the bearer adapted to be secured to the center sill and side of the car, means along the upper edge of the bearer adapted to be secured to the side stakes, and seat portions near the upper edge of the cross bearer for assisting in supporting the hopper sheets.
- 50 17. A cross bearer for a freight car having an upper and a lower member and integral diagonals between the same, brackets on the upper member of the cross bearer, arms secured to said brackets and adapted to extend upwardly for attachment to side stakes of the car, a diagonal being positioned 55 beneath each of said arms and extending in the same direction, and further diagonals near the ends of the cross bearer extending downwardly and inwardly from the said upper member.
- 5 18. In a freight car construction, a cast 70 steel cross bearer having a horizontally extending top member provided with a horizontal flange and a substantially vertical web portion, hopper sheets, the said cross bearer fitting down between the hopper sheets and the latter being riveted to the web portion of the top member below the flange thereof.
19. In a car construction, a center sill and side sills, a cross bearer resting on the center sill and rigidly secured thereto and to the side sills, said bearer being provided with a substantially horizontal top flange, and hopper sheets rigidly secured to the cross bearer and enclosing all but the top 80 flange thereof.
20. In combination, a one-piece cross bearer provided with brackets on its upper edge, arms connected to said brackets, the upper portion of said cross bearer provided with 90 webs beneath said brackets, flanges beneath said webs, hopper sheets having cut-out portions along their upper edges, said hopper sheets resting on said flanges, the cut-out portions extending beyond said webs and the 95 said hopper sheets being riveted along the upper portions of the cross bearer.
21. A cross bearer for railway hopper cars having seats directly beneath its upper edge adapted to assist in supporting hopper 100 sheets of the car.
22. In a railway car, the combination with side stakes, of struts extending downwardly and inwardly from the side stakes for bracing the latter, and a cross bearer provided 105 with upwardly extending plate-like portions disposed in planes forming oblique angles with the sides of the car, the lower ends of said strut members being respectively secured to said plate-like portions. 110
23. In a railway car, the combination with side stakes, of struts extending downwardly and inwardly from the side stakes for bracing the latter, and a cross bearer having a plurality of brackets, each of said brackets 115 having an upwardly and outwardly extending plate-like portion disposed in a plane forming an oblique angle with the adjacent side of the car and a substantially vertical reinforcing portion, the lower ends of said struts being respectively secured to the plate-like portions of the brackets.
24. In a railway car, the combination with side stakes, of struts extending downwardly and inwardly from the side stakes for bracing the latter, and a cross bearer having a substantially horizontal top flange and bracket members extending upwardly therefrom, each of said brackets having a plate-like portion disposed in a plane forming an 120 130

- oblique angle with said top flange, the lower ends of said strut members being rigidly secured to said plate-like portions of the brackets.
- 5 25. In a railway car, the combination with side stakes, of struts extending downwardly and inwardly from the side stakes for bracing the latter, and a cross bearer having a substantially horizontal top flange and bracket members extending upwardly therefrom, said struts being respectively secured to the bracket members and adjacent portions of the said top flange.
- 10 26. In a railway car, the combination with side stakes, of struts extending downwardly and inwardly from the side stakes for bracing the latter, and a cross bearer having a substantially horizontal top flange and bracket members extending upwardly therefrom, each of said bracket members having a plate-like portion disposed in a plane forming an oblique angle with the top flange, each of said struts having angularly disposed portions respectively secured to the top flange of the bearer and the plate-like portion of the adjacent bracket.
- 15 27. In a railway car, the combination with side stakes, of struts extending downwardly and inwardly from the stakes for bracing the latter, of a cross bearer having an upper member provided with a substantially horizontal top flange and a substantially vertical web portion, said member having upwardly extending brackets comprising plate portions disposed in plates oblique to the said horizontal flange, and reinforcing flanges extending downwardly from said flange on opposite sides of said web portion respectively constituting continuations of the plate-like portions of the brackets, the lower ends of said struts being rigidly secured to said plate-like portions.
- 20 28. In a railway car, the combination with a center sill, of a transverse load carrying member extending from one side of the car to the other and having a substantially horizontal portion resting upon the top of the center sill, said member being integrally formed with depending brackets disposed on opposite sides of the center sill, each of said brackets having a plate portion rigidly secured to the adjacent side of the center sill and extending upwardly above said horizontal portion of said member.
- 25 29. In a railway car, the combination with a center sill, of a transverse load carrying member extending from one side of the car to the other, said member being provided with a substantially horizontal portion resting upon the top of the center sill and an upwardly extending web portion, and brackets formed integrally with said member and disposed on opposite sides of the center sill, each of said brackets having a plate-like portion secured to the adjacent side of
- the center sill and merging with the web portion of the member above the horizontal portion thereof.
- 30 30. In a railway car, the combination with a center sill, of a transverse load carrying member extending from one side of the car to the other, said member being provided with a substantially horizontal portion resting upon the top of the center sill and an upwardly extending web portion, and brackets formed integrally with said member and disposed on opposite sides of the center sill, each of said brackets having a plate-like portion secured to the adjacent side of the center sill and a reinforcing flange disposed in substantially the plane of the web portion of the member, said plate-like portions of the brackets being of substantially triangular shape and merging with the said web portion above the said horizontal portion.
- 35 31. In a railway hopper car, the combination with a center sill, of a cross bearer extending from one side of the car to the other above the center sill, said bearer having an upper member provided with a substantially horizontal flange and with a portion extending downwardly therefrom, and hopper sheets respectively secured to said portion below said horizontal flange and diverging downwardly on opposite sides of the bearer.
